CLAIM

The ornamental design for an incontinence guard for males, as shown and described.

DESCRIPTION

FIG. 1 is a front elevational view of an incontinence guard for males, showing my new design;

FIG. 2 is a rear elevational view thereof;

FIG. 3 is a front perspective view thereof;

FIG. 4 is a side elevational view thereof from the left of FIG. 1;

FIG. 5 is a front perspective view thereof in folded condition;

FIG. 6 is a rear perspective view thereof in folded condition;

FIG. 7 is a side elevational view thereof, from the left of FIG. 3, in folded condition;

FIG. 8 is a side elevational view thereof, from the right of FIG. 3, in folded condition;

FIG. 9 is a top plan view thereof in folded condition; and

FIG. 10 is a bottom plan view thereof in folded condition.
